UNITED STATES PATENT OFFICE

2,447,345

APPARATUS FOR SPINNING AND WINDING
TEXTILE THREADS

René Jacques Henri Kovacs, Paris, France

Application September 17, 1945, Serial No. 616,822
In France August 2, 1944Section 1, Public Law 690, August 8, 1946
Patent expires August 2, 1964

6 Claims. (Cl. 57—71)

1

Nowadays the spinning of textiles such as wool, cotton, and similar products is obtained on flyers after which the thread is wound up on spools on winding frames.

My invention has for its object a machine allowing the simultaneous execution of both spinning and winding operations. My improved machine has a reduced bulk, is of a very low cost price and moreover it considerably simplifies said operations. In said machine the roving does not rotate but it is caused to twist under the action of the rotary motion of the machine which leads to a much more regular twist of the thread.

My improved machine includes chiefly a frame adapted to rotate around a horizontal axis and carrying a device providing for the reciprocation of a slider through a line perpendicular to the axis of rotation while a friction driving cylinder rotates around an axis parallel with the line along which the slider reciprocates, means being provided for controlling the reciprocation of the slider and for rotating the driving cylinder and a spool carrying shaft being provided which is parallel with the driving cylinder and yieldingly urged towards same.

Further interesting features of my invention will appear in the reading of the following description of a form of execution given by way of example and illustrated in accompanying drawing wherein:

Fig. 1 is a side view thereof partly sectional.

Fig. 2 is an end view from the right hand side of Fig. 1.

Fig. 3 is a diagrammatic cross-section illustrating the operation of the machine.

The machine includes a stationary support 1 of aluminium for instance inside which may rotate a horizontal shaft 2 which may be of soft steel and which is caused to rotate through any suitable means such as a treadle or a motor. In the present case, I have shown it as controlled by an electric motor 3. This shaft 2 passes through a stepped pulley 4 rigidly secured to the support 1 and is rigid with a frame 5 the front end of which ends in the form of a metallic ring 6. The frame 5 carries a gear box 7 inside which a shaft 8 is rotatively carried in a bracket 9 secured to the frame 5. The shaft 8 carries another stepped pulley 11 connected with the pulley 4 through a belt 12.

The gears inside the box 7 transmit the rotation of the shaft 8 on one hand to two guiding cylinders 13, 13' provided with crossed helical grooves (Fig. 2) over which may reciprocate the sliders 14, 14' guided so as to be prevented from

2

moving around the cylinders 13, 13' and the rotation of the shaft 8 is on the other hand transmitted through the box 7 to the friction driving cylinder 15 covered with a friction material such as cardboard, rubber or the like and parallel with the cylinders 13—13'; the axes of said cylinders 13, 13' and 15 being perpendicular to the rotary axis of the horizontal shaft 2.

The gearing contained inside the box 7 may be of any type. It has been assumed in the present case by way of example that the shaft 8 ends with a worm 16 (Fig. 2) engaging a helical wheel 17 to the axis of which is keyed a pinion 18 providing for the rotation of the guiding cylinder 13 and meshing with a pinion 19 driving the friction operating cylinder 15 and meshing in its turn with the pinion 18' which provides for the rotation of the guiding cylinder 13'.

Of the two sliders 14 and 14', only the slider 14 is operative and is provided with an opening 21 for the passage of the thread while the slider 14' serves only as a balancing weight as required for the high rotational speeds of the machine. The two sliders 14, 14' move in reverse directions along the guiding cylinders 13, 13' and cross one another at half way of said cylinders 13, 13'.

The friction operating cylinder 15 is mounted in an easily interchangeable manner whereby it may be replaced rapidly by another cylinder of a different diameter with a view to adjusting the speed of formation of the spool. This removability may be obtained by any suitable means. For instance, in Fig. 1 in which the guiding cylinders have not been shown in the drawing for sake of clearness, it is apparent that the friction cylinder 15 carries at its ends projections provided with transverse pins 22, 23 adapted to engage notches cut in the sockets 24, 25. The notched socket 24 which is controlled by the pinion 19 cannot move longitudinally whereas the socket 25 is slidably mounted inside the frame 5 and carries an axial rod 26 the socket 25 being urged upwardly by a spring 27; said rod 26 ends in a milled knob 28 bearing against the casing 29 forming a counterweight balancing the gear box 7. Obviously it is possible to draw the knob 28 out for easily releasing the friction cylinder 15 which may then be replaced by another cylinder.

The shaft 2 is provided with a longitudinal bore 50 which receives a stub shaft 31, urged by a spring 32 also housed inside said bore. The stub shaft 31 carries a fork 33 diametrically guided by any conventional means such as key and slot engagement of the stub shaft 31 inside the frame 5 and carrying, through the agency of notches for in-

stance, the spool carrying spindle 34 parallel with the friction cylinder 15 and over which it is possible to insert a tube, made of cardboard or the like adherent material as shown at 35. Obviously the spring 32 urges the spool carrying spindle 34 together with the tube 35 and the spool under formation against the friction cylinder 15.

At the end of the shaft 8 controlling the worm and inside the stepped pulley 11 is provided an adjustable brake constituted by two fibre washers 36, 37 arranged to either side of one of the pulley flanges. The washer 38 bears against the collar on a sleeve 39 rotating together with the shaft 8 and provided with a helical thread engaging the nut 39 acting through the agency of a spring 41 on a washer 37.

Lastly in Fig. 3 is illustrated the manner of providing for the guiding of the slider 14 over the guiding cylinder 13. This slider is provided at its rear end with two pins 40 enclosing a rigid guiding rod 42. This arrangement obviously prevents the slider from rotating with reference to the guiding cylinder 13. On the other hand, in order to provide for the guiding of the slider inside the helical groove of the cylinder 14, there is arranged a guiding member 43 engaging the grooves through a certain length, a small collar 44 on said member and a tail piece 45 therefor forming a projection engaging loosely a perforation in the threaded block 46 screwed inside a bore of the slide 14. I obtain thereby an excellent guiding for the slider inside the helical grooves of the guiding cylinder 13 chiefly at the extreme points at which the slider ends its movement in a direction and beginning its movement in the reverse direction. As a matter of fact as the collar 44 has the possibility of moving up to the surface of the threaded block 46 and by reason of the possibility for the projection 45 to rock inside said block, the guiding member 43 may follow the groove while rocking slightly with reference thereto without leaving it and without being wedged.

The operation of the machine is as follows:

The roving 48 (Fig. 3) coming from a tensioning guiding member 49 passes through the opening 21 in the slider 14 and is engaged between the frictional operative cylinder 15 and the card-board tube 35 which is at this moment urged into contact with the cylinder 15 and the end of the roving is maintained in a slot provided in said card-board tube 35; after a few revolutions have been executed by hand the machine is started. The arrangement formed by the shaft 2, the frame 5 and the fork 33 is started rotating at a speed which is for instance of the order of 700 R. P. M., whereas the pulley 11 which rotates under the action of said rotary movement around the stationary pulley 4 provides for the rotation of the guiding cylinders 13, 13' and of the friction cylinder 15. The slider 14 reciprocates along the cylinder 13 whereby it provides for the twisting of the thread and its winding around the spindle 34 through the frictional action between said spindle and the friction cylinder 15 and then between the spool 51 thus being formed and this same friction cylinder.

When the belt 12 is caused to pass from one step of the pulleys 4 and 11 on to the other, this leads obviously to the obtention of two different speeds for the shaft 8, which modifies by way of consequence the twist of the thread and the speed of winding.

What I claim is:

1. A machine for spinning and winding tex-

tile threads including a stationary support, a frame rotatably mounted at one end of an horizontal axis in said support and open at its opposite end, means controlling the rotation of said frame, a friction winding cylinder carried by said frame near the open end thereof, the axis of said cylinder being perpendicular to the axis of rotation of the frame, a slider mounted for reciprocating movement across the open end of said frame in a direction parallel with the axis of the cylinder and in front of said cylinder and receiving the roving directly from the outside, means operated incident to the rotation of the frame with respect to the stationary support for causing reciprocating movement of the slider and rotation of the winding cylinder, a spool carrying shaft mounted in the frame in a plane parallel with the cylinder axis, means positively and yieldingly urging said shaft towards said cylinder, and guiding means carried by the slider for directing the roving between the cylinder and the spool carrying shaft.

2. A machine for spinning and winding textile threads including a stationary support, a frame rotatably mounted at one end on an horizontal axis in said support and open at its opposite end, means controlling the rotation of said frame, a friction winding cylinder carried by said frame near of the open end thereof, the axis of said cylinder being perpendicular to the axis of rotation of the frame, a first guiding cylinder provided with crossed helical grooves and disposed parallel to the friction winding cylinder in front of said cylinder, a first slider engaging said grooves, reciprocating along said first guiding cylinder and receiving the roving directly from the outside, a second guiding cylinder provided with crossed helical grooves and symmetrically arranged with respect to said first guiding cylinder, a second slider engaging the grooves of said second guiding cylinder and operating as a counter-weight for the first slider, means operated incident to rotation of the frame with respect to the stationary support for transmitting rotary motion to the winding cylinder and to the guiding cylinders, a spool carrying shaft carried in the frame in a plane parallel with the winding cylinder axis, means positively and yieldingly urging said shaft towards said cylinder, and guiding means carried by the slider for directing the roving between the cylinder and the spool carrying shaft.

3. A machine as claimed in claim 1 provided with means for removably and interchangeably securing the friction winding cylinder in the rotatable frame.

4. A machine for spinning and winding textile threads including a stationary support, a stationary stepped pulley fixed to said support, a frame rotatably mounted at one end on an horizontal axis in said support concentrically to said pulley and open at its opposite end, means controlling the rotation of said frame, a friction winding cylinder carried by said frame near of the open end of the same, the axis of said cylinder being perpendicular to the axis of rotation of said frame, a slider mounted for reciprocating movement across the open end of said frame in a direction parallel with the axis of said cylinder and receiving the roving directly from the outside, a stepped pulley mounted on said frame, a belt connecting the stationary stepped pulley with the stepped pulley on the frame, and a transmission gear carried by the frame and op-

erated by the stepped pulley on the frame to cause reciprocation of the slider and rotation of the winding cylinder.

5. A machine for spinning and winding textile threads including a stationary support, a bored horizontal shaft rotatably mounted in said support, a frame fixed to said shaft at one end and open at its opposite end, means controlling the rotation of said frame, a friction winding cylinder carried by said frame near the open end thereof, the axis of rotation of said cylinder being perpendicular to the axis of rotation of the frame, a slider mounted for reciprocating movement across the open end of said frame and receiving the roving directly from the outside, means operated incident to rotation of the frame with respect to the stationary support for causing reciprocating movement of the slider and rotation of the winding cylinder, a shank located in the bore of the horizontal shaft, a fork on said shank, a spool carrying shaft removably mounted in said fork, a spring located in the bore and urging the fork and the spool carrying shaft towards said winding cylinder, and guiding

means carried by the slider for directing the roving between the cylinder and the spool carrying shaft.

6. A machine as claimed in claim 4 comprising on the frame a counter weight diametrically opposed to the transmission gear.
